United States Patent Office

Des. 232,250
Patented July 30, 1974

232,250

OCCUPANT PROPELLED AMUSEMENT BALL

Bradley J. Caylor, 1340 Kilrush Court,
Pinole, Calif. 94564

Filed Sept. 18, 1972, Ser. No. 290,225

Term of patent 7 years

Int. Cl. D21—01

U.S. Cl. D34—15 AJ

FIG. 1 is a perspective view of an occupant propelled amusement ball showing my new design;

FIG. 2 is a similar view thereof partly in section;

FIG. 3 is a top plan view of the lower half thereof; and

FIG. 4 is a bottom plan view of the top half thereof. I claim:

The ornamental design for a occupant propelled amusement ball, as shown.
